(57) CLAIM

I claim the ornamental design for a rifle breech bolt, as shown and described.

DESCRIPTION

FIG. 1 is a front elevational view of a rifle breech bolt showing my new design;

FIG. 2 is a back elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front perspective view thereof; and,

FIG. 8 is a back perspective view thereof.
